UNITED STATES PATENT OFFICE.

JOHN F. ABEL, OF BURLINGTON, IOWA.

ATTACHMENT FOR CARBUREETERS.

1,269,146.

Specification of Letters Patent. Patented June 11, 1918.

Application filed March 27, 1917. Serial No. 157,783.

To all whom it may concern:

Be it known that I, JOHN F. ABEL, of Burlington, in the county of Des Moines and State of Iowa, have invented certain new and useful Improvements in Attachments for Carbureters; and I do hereby declare the following to be a full, clear, and exact description of the invention, such as will enable others skilled in the art to which

10 it appertains to make and use the same.

This invention relates to carbureters for internal combustion engines, and the object of the invention is to provide an improved, simple and efficient attachment for introducing kerosene, air and water into the carbureted fuel within the carbureter whereby greater power will be produced with a saving of fuel and a minimum formation of carbon in the cylinders.

15 20 In the accompanying drawing, Figure 1 is an elevation partly in section showing my improved attachment secured in place on a carbureter. Fig. 2 is a sectional view of the carbureter.

25 Referring to the drawings, 1 designates a carbureter of any preferred form having an inlet 2 through which liquid fuel is supplied; an outlet 3 connecting with the intake of the engine; and an air induct 4. The 30 usual throttle valve 5 controls the passage of the gasoline or other liquid fuel to the engine manifold and a needle valve 6 regulates the opening from the reservoir 8 to the upper portion of the carbureter.

35 At a point in the carbureter casing above the reservoir 8 thereof and between the needle valve 6 and the throttle valve 5 I secure one end of a coupling 9, one branch 10 thereof communicating with pipe 12 leading to the

40 receptacle 13 for kerosene, which receptacle is located at any convenient point. The other branch 14 of the coupling communicates with a pipe 15 leading to the radiator and is designed to supply water therefrom.

45 Heated air may be entrained into the water pipe 15 through a pipe 16 connected with the exhaust 16' and joining the pipe 15 intermediate the intake and discharge into the branch 14. The casing of the exhaust has

50 a number of perforations 25 through which fresh air is drawn by the suction created

by the flow of water through the pipe 15. The point of supply of the kerosene to the coupling is further removed from the carbureter than that of the air and water so as 55 to avoid premature ignition. A check valve 17 may be provided at any convenient point in the pipe 15 to prevent water running into the carbureter when the engine is at a standstill, and I also provide a valve 18 60 to regulate the flow of kerosene from the receptacle 13. For controlling the amount of air, water, and kerosene supplied to the carbureter a valve 19 is placed at the point of connection between the coupling 9 and 65 the carbureter casing, manipulation of the valve being readily effected by a rod 20 extending to the front of the machine.

By the arrangement set forth I am enabled to introduce into the carbureted fuel 70 sufficient air and water to effect a complete moistening of the mixture supplied to the engine, the commingling of the air and water from the radiator at a point between the needle valve and the throttle valve insuring a mixture which is thoroughly carbureted at the time it passes to the engine intake. The kerosene supplied to the fuel along with the air and water produces a superior gaseous product with increased 80 power and with the further advantage that carbonization is rendered negligible.

I claim as my invention:

In combination with an internal combustion engine and a carbureter therefor, the 85 latter having a fuel inlet and a valve controlling such inlet, an outlet, and a valve therefor, an oil receptacle, means for supplying moistened oil laden air to said carbureter comprising a coupling secured at 90 one end to the carbureter casing intermediate said fuel inlet and said outlet, said coupling having a branched connection with the radiator of a motor vehicle to receive, water therefrom, a pipe for supplying air 95 heated by the engine exhaust to said branched connection, and a second branched connection from said coupling to said oil reservoir.

In testimony whereof, I have signed this 100 specification.

JOHN F. ABEL.
